(57) **CLAIM**

The ornamental design for an adaptor for saw, as shown and described.

DESCRIPTION

FIG. 1 is a top plan view of an adaptor for saw showing my new design;

FIG. 2 is a bottom plan view thereof;

FIG. 3 is a left side elevational view thereof (with the right side being a mirror image);

FIG. 4 is a rear, left side perspective view thereof;

FIG. 5 is a front, left side perspective view thereof;

FIG. 6 is an additional rear, left side perspective view thereof;

FIG. 7 is a rear elevational view thereof; and,

FIG. 8 is a front elevational view thereof.

The broken lines depict portions of the adaptor for a saw that are not part of the claimed design.
